UNITED STATES PATENT OFFICE.

EDGAR BEAUMONT JARVIS, OF TORONTO, CANADA.

REINFORCED TRUSS FOR CONCRETE.

No. 811,927.

Specification of Letters Patent.

Patented Feb. 6, 1906

Application filed December 15, 1904. Serial No. 236,987.

To all whom it may concern:

Be it known that I, EDGAR BEAUMONT JARVIS, of the city of Toronto, in the county of York, in the Province of Ontario, Canada, have invented certain new and useful Improvements in Reinforcing-Trusses for Concrete, of which the following is the specification.

My invention relates to improvements in reinforcing-trusses for concrete; and the object of the invention is to devise a truss of this class which will be strong, efficient, and cheaply made; and it consists, essentially, of an I-beam provided with a series of openings 5 and bars extending underneath the I-beam and having obliquely-arranged ends extending upwardly and outwardly at each end through the openings beyond the upper side of the I-beam, the said bars being arranged adjacent to each other with the shortest in the center next the I-beam and the truss being otherwise arranged and constructed in detail, as hereinafter more particularly explained.

25 Figure 1 is a perspective view showing my improved truss. Fig. 2 is a longitudinal section of the truss. Fig. 3 is a cross-section.

In the drawings like characters of reference indicate corresponding parts in each figure.

30 A is the I-beam, which in the present instance I show with a series of openings 2, 3 3, and 4 4.

a is the central bar, which is provided with obliquely-shaped ends a' a', which extend 35 through the openings 2 2.

It will be noticed that the ends a' extend in a direction outwardly toward the end of the I-beam and are preferably provided with spurs a².

40 b is the bar immediately underneath the bar a, such bar being longer than the bar a and having the obliquely-shaped ends b' b', extending through the openings 3 3 and provided with spurs b² b².

45 5 5 are separating-blocks separating the bar b from the bar a.

c is a third bar located underneath the bar b and having the obliquely-arranged ends c' c' extending through the openings 4 4 and 50 provided with spurs c² c². The bar c is separated from the bar b by the separating-blocks 6 6.

Such a truss as I describe when embedded in cement is extremely strong, and the ob-

lique portions of the bars, it will be seen, take 55 the shearing strain.

Although I show three bars a, b, and c it will of course be understood that any number of bars may be provided depending on the length of the truss and that corresponding openings will be made in the truss to suit the number of bars.

Although I show the beam A as an I-beam, it will be understood that it may be of any cross-sectional form, such as a channel-beam. 65

I preferably make each of the bars, including the oblique portions, gradually greater in cross-sectional area, starting at the center with the lighter bar and increasing in weight as they approach the end of the truss, 70 thereby saving metal in the construction of the truss.

It will of course be understood that the shearing strain at the center is less than at the ends, and for this reason I am enabled to 75 produce a strong and yet economical truss.

It will be noticed that the ends of each of the oblique portions of the bars are bent to form spurs and such spurs, as will be readily understood, form an efficient means for preventing the oblique portions drawing through the cement. It will also be noticed that the bars a, b, and c are held apart by blocks and that openings 7 are provided between the oblique ends of the bar underneath the beam, 85 and I arrange my truss especially in this manner, for the reason that the cement when poured in will fill the interstices between the blocks and the ends of the bars and thereby cementing the different members together 90 and making a unitary truss.

Another advantage of my invention is that for convenience of transportation all the bars may be shipped in straight form and bent and placed in position in the beam where the 95 work is going on.

What I claim as my invention is—

1. In a reinforcing-truss for concrete, the combination with the beam having a plurality of openings, of a bar extending underneath the beam and upwardly and outwardly through the openings and having obliquely-arranged ends oppositely inclined toward the ends of the beam as and for the purpose specified. 100

2. In a reinforcing-truss for concrete, the combination with the beam having a plurality of openings, of a bar extending under-

neath the beam and upwardly and outwardly through the openings and having obliquely-arranged ends oppositely inclined toward the ends of the beam and provided with 5 spurs as and for the purpose specified.

3. In a reinforcing-truss for concrete, the combination with the I-beam having a plurality of openings, of a bar extending underneath the beam and upwardly and outwardly through the openings and having obliquely-arranged ends oppositely inclined toward the ends of the beam as and for the purpose specified.

4. In a reinforcing-truss for concrete, the combination with the beam having a plurality of openings, of a plurality of bars extending underneath the beam and upwardly and outwardly through the openings, the shortest being located in the center, each of the bars 20 having obliquely-arranged ends extending through the openings and oppositely inclined toward the ends of the beam as and for the purpose specified.

5. In a reinforcing-truss for concrete, the combination with the beam having a plurality of openings, of a plurality of bars extending underneath the beam and upwardly and outwardly through the openings, the shortest being located in the center, each of the bars 30 having obliquely-arranged ends extending through the openings and oppositely inclined toward the ends of the beam and separating-blocks located between the portions of the bars extending underneath the beam as and for the purpose specified.

6. In a reinforcing-truss for concrete, the

combination with the main bar or beam, of supplemental bars suitably held thereto and provided with obliquely-arranged ends, the said bars increasing in cross-sectional area 40 from the center outwardly as and for the purpose specified.

7. In a reinforcing-truss for concrete, the combination with the beam having a plurality of openings, of a plurality of bars extending underneath the beam and upwardly and outwardly through the openings, the shortest being located in the center, each of the bars having obliquely-arranged ends extending 45 through the openings and oppositely inclined toward the ends of the beam and separating-blocks located between the portions of the bars extending underneath the beam, the said separating-blocks and ends of the bars being so arranged as to provide openings 50 between the bars themselves, and the bars and the beam, and ends of the bars as and for the purpose specified.

8. In a reinforcing-truss for concrete, the combination with the beam having a plurality of openings, of a bar extending underneath the beam and upwardly and outwardly through the openings and having obliquely-arranged ends oppositely inclined toward the ends of the beam and held in place 60 by the contact of the upper and lower sides of the obliquely-shaped ends on the edges of the openings as and for the purpose specified.
